UNITED STATES PATENT OFFICE

GEORGE S. YOUNG, OF THE UNITED STATES ARMY.

FOLDING TABLE.

970,774.

Specification of Letters Patent. Patented Sept. 20, 1910.

Application filed August 30, 1909. Serial No. 515,280.

To all whom it may concern:

Be it known that I, GEORGE S. YOUNG, United States Army, citizen of the United States, have invented certain new and useful 5 Improvements in Folding Tables, of which the following is a specification.

This invention comprehends certain new and useful improvements in furniture, and the invention has for its object an improved 10 table which embodies a novel arrangement of parts whereby it is rendered susceptible of being readily folded into a very compact form, so as to occupy a minimum amount of space and thus be capable of being expeditiously carried from place to place as desired.

A further object of the invention is a folding table, the top of which is composed of a middle and side sections, the latter being 20 provided at their under faces with reinforcing frames that are arranged to telescope, so as to form a closed receptacle when the parts of the table are folded, the legs being inclosed within such receptacle in order 25 to be protected from possible injury.

A still further object of the invention is a device of this character which embodies to a marked degree the characteristics of simplicity, durability and strength, and which 30 is particularly convenient and will at once recommend itself to campers, paper hangers, and others having use for folding tables.

With these and other objects in view that will more fully appear as the description appears, the invention consists in certain constructions and arrangements of the parts that I shall hereinafter fully describe and then point out the novel features of in the appended claims.

For a full understanding of the invention and the merits thereof and also to acquire a knowledge of the details of construction reference is to be had to the following description and accompanying drawing, in 45 which:

Figure 1 is a perspective view of my improved table; Fig. 2 is a similar view showing the table folded; Fig. 3 is a bottom plan view of the table; Fig. 4 is a similar view 50 showing the legs and brace bars folded against the leaves preparatory to folding the latter; and, Fig. 5 is a transverse section on the line 5—5 of Fig. 2.

Corresponding and like parts are referred 55 to in the following description and indicated

in all the views of the drawing by the same reference characters.

The top of my improved table is composed of a middle leaf or section 1 and side leaves or sections 2 and 2', the leaves being connected together by hinges 3, so as to be adapted to be folded. The middle leaf has a bar 4 pivoted at its middle point to the under side thereof and adapted to extend transversely beneath the table top, so that its ends project beyond the side edges of the middle leaf and overlap the respective side leaves to maintain the leaves extended, the projecting ends of the bar being preferably received in oppositely facing hooked stops 5 secured to 70 the under faces of the side leaves, as shown. The bar 4 is turned longitudinally of the middle leaf in the customary manner, in order to release the side leaves when the same are to be folded.

The side leaves are provided at their lower faces with depending marginal strips or flanges that constitute similar reinforcing frames 6 and 6'. Each of these reinforcing frames has three sides and comprises a strip 7 that is disposed along the free longitudinal edge of the side leaf, and transverse strips 8 which extend perpendicularly from the longitudinal strip at the opposite ends of the side leaf and terminate flush with the hinged edge thereof. The strips forming the frame 6 are set back slightly from the corresponding edges of the leaf 2, so that the said frame is smaller than the other frame 6' and is adapted to 80 fit telescopically within the latter when the parts of the table are folded.

Attention is here directed to the fact that the middle leaf 1 is substantially equal in width to the width of the marginal strips of the side leaves, and is arranged to be turned against the ends of the transverse strips 8 of the frame 6', whereby to complete such frame and thus completely inclose the frame 6, the table when folded 100 being in the form of a closed receptacle (see Fig. 2).

The legs 9 of the table are substantially inverted L-shaped and are provided at their upper ends with perpendicularly disposed base portions 10 which extend transversely of the lower faces of the respective side leaves and are arranged inside of and in close proximity to the transverse strips of the respective reinforcing frames. The 110

bases are secured to the side leaves by hinges 11 which admit of the legs being turned about transverse axes, so as to be swung upwardly against said leaves and entirely within the respective frames. When the legs are in operative positions, the bases abut against the adjacent transverse strips 8 to limit the outward swinging movement thereof about the hinges 11. Attention is also directed to the fact that the base portions of the legs are spaced apart from the transverse strips 8 in the folding positions of the legs, whereby to afford clearance for the transverse strips 15 of the frame 6 when the parts are folded. The two legs carried by each of the side leaves are positioned at different distances from the corresponding longitudinal strip 7, thus causing said legs to operate in parallel planes and permitting the free ends of the legs to lie side by side when folded. Both legs carried by the side section 2^a are spaced apart from the longitudinal strip 7 of the frame 6^a sufficiently 20 to afford ample clearance for the longitudinal strip of the smaller frame 6. The frame 6 fits snugly within the seating recess which is thus provided between the frame 6^a and the adjacent folded legs, whereby 25 to assist materially in retaining the leaves folded against accidental spreading movement.

A pair of spring brace bars 12 are provided on each of the side leaves and are notched at one end, as indicated at 13, to engage studs 14 outstanding from the legs 9, thus maintaining said legs rigidly in operative positions. At their other ends the braces have pivotal connections with ears 15 depending from the side leaves at longitudinally spaced points. The ears are set at oblique angles to the length of the side leaves and converge inwardly and laterally, the brace bars operating substantially in the planes of the ears, which planes are oblique to the planes of movement of the legs. By virtue of this arrangement the braces of each pair tend to cross when folded against the side leaf; however in practice one of the braces of each pair is swung laterally so as to clear the other brace and to press frictionally against the same, thereby insuring of both of the braces being retained in folded positions against accidental displacement.

The manner of folding a table constructed in accordance with my invention is as follows:—The brace bars 12 are lifted out of engagement with the studs 14 and are swung about their pivots and against the under faces of the side leaves, one of the brace bars of each pair being sprung into engagement with the other bar, as before described, so as to effectually retain said bars in place. The legs 9 being released by the braces are

turned against the side leaves and within the respective reinforcing frames carried thereby. The bar 4 is then turned longitudinally with respect to the middle leaf 1, whereupon the side leaves are folded upon each other, the 70 reinforcing frame 6 fitting within the frame 6^a and in the space between the latter and the corresponding pair of folded legs. In this position the parts of the table form a box-like receptacle within which the legs 75 and braces are entirely inclosed, so as to be protected from injury during shipping or the like.

Among the many advantages attained with the present invention, attention is particularly directed to the fact that a table is provided which may be expeditiously folded into a compact form, which embodies to a marked degree the characteristics of simplicity, durability and strength and consists 80 of comparatively few parts that are not likely to get out of order through repeated operation; and which may be easily and cheaply manufactured so as to warrant its 85 general adoption. It is also to be observed 90 that camp paraphernalia, tools, and other articles may be packed within the receptacle formed by the folded table, and thus be conveniently transported from place to place. 95

Having thus described the invention what is claimed as new is:

1. A folding table comprising a foldable top consisting of hinged leaves, reinforcing frames provided at the lower faces of the 100 leaves and fitting telescopically one within the other when the leaves are folded, and legs carried by the respective leaves and foldable within the reinforcing frames, one of the leaves being provided with a seating 105 recess in which the reinforcing frame of the other leaf is arranged to fit snugly, as and for the purpose specified.

2. A folding table comprising a foldable top consisting of hinged leaves, reinforcing 110 frames provided at the lower faces of the leaves and fitting telescopically one within the other when the leaves are folded, pairs of legs carried by the respective leaves and foldable within the adjacent reinforcing 115 frames, the legs connected to one leaf being spaced apart from the adjacent reinforcing frame to provide a seating recess for the reception of the other reinforcing frame.

3. A folding table, comprising a foldable 120 top consisting of hinged leaves, reinforcing frames provided at the lower faces of the leaves and fitting telescopically one within the other when the leaves are folded, and legs connected to the leaves and foldable 125 within the adjacent reinforcing frames, the legs attached to one of the leaves having enlarged bases bearing against the adjacent reinforcing frame in the operative position of the legs, the bases being spaced apart 130

from said reinforcing frame when the legs are folded, to provide seating recesses for the reception of the other reinforcing frame.

4. A folding table comprising a top, foldable legs, foldable braces pivotally connected at one end to the top and detachably engaged at their other ends to the legs, the adjacent braces engaging each other when folded in order to be held against accidental displacement.

5. A folding table, comprising a top, pairs of legs pivotally connected to the top and foldable thereagainst, pairs of foldable braces pivoted at one end to the top and having detachable connection at their other ends with the legs to maintain the latter extended, one brace of each pair being of spring formation and bearing frictionally against the other brace when the braces are folded, whereby to maintain the braces against accidental displacement.

6. A folding table comprising a top com-

posed of separate leaves hingedly connected together, reinforcing frames secured to the lower faces of the leaves and fitting telescopicly one within the other when the leaves are folded, legs pivoted to the leaves and adapted to be folded against the same and within the respective frames, and pairs of spring brace bars carried by the respective leaves and pivoted at one end thereto and having detachable engagement at their other ends with the corresponding legs to maintain the latter extended, the brace bars of each pair being arranged to be folded against the corresponding leaf and engaging each other frictionally whereby to be held against displacement.

In testimony whereof I affix my signature in presence of two witnesses.
